HANDLE-EQUIPPED CONTAINER

James R. Young, 913 Forsythe Ave., Toledo 5, Ohio
Filed Oct. 11, 1960, Ser. No. 61,987

1 Claim. (Cl. 229—52)

This invention relates to milk cartons.

One object of this invention is to provide a milk carton having a handle attached to one side thereof to assist the user in pouring milk from the carton and to prevent slipping and possible dropping of the carton.

Another object is to provide a milk carton of the foregoing character wherein the handle is secured at its upper and lower ends to the carton and has foldable portions enabling the handle to be folded flat against the carton, so that the handle-equipped carton of the present invention occupies substantially the same space as conventional cartons not equipped with such handles.

Other objects and advantages of the invention will become apparent during the course of the following description of the accompanying drawing, wherein:

FIGURE 1 is a side elevation of a milk carton equipped with a foldable handle, according to one form of the invention, with the handle in its folded position;

FIGURE 2 is a rear elevation of the handle-equipped carton of FIGURE 1, with the handle folded;

FIGURE 3 is a side elevation similar to FIGURE 1, but with the handle in its unfolded position; and

FIGURE 4 is a fragmentary side elevation of a modification of the invention, showing in solid lines the handle in its folded position and in dotted lines the handle in its unfolded position.

Hitherto, milk cartons of waxed cardboard have come into common use and have found ready acceptance with the buying public. In the use of such cartons, however, particularly in the two-quart sizes, the manipulation of the carton for pouring has been difficult because of the bulk of the carton, particularly for persons with small hands or short fingers. As a result, accidents have frequently occurred by the dropping of the carton as a result of its slipping from the grasp of the fingers, and accuracy of pouring has been difficult even when such slippage has not occurred. Separate holders have previously been provided for receiving such cartons, but have not come into general acceptance by the public because of the inconvenience of having to look for a holder every time a carton of milk was to be used. The present invention eliminates these disadvantages by providing a milk carton with a "built-in" folding handle which when not in use folds flatly against the side of the carton so as to occupy substantially no more space than a carton not equipped with such a handle.

Referring to the drawings in detail, FIGURES 1 to 3 inclusive show a handle-equipped milk carton, generally designated 10, according to one form of the invention, as consisting generally of a receptacle unit 12 and a foldable handle unit 14 secured thereto. The receptacle unit 12 is of vertically-elongated box-shaped form with front and rear walls 16 and 18 interconnected by lateral walls 20 and by a bottom wall 22. The walls 16, 18 and 20 are interconnected at their upper ends by a top structure, generally designated 24. The top structure 24 consists of slanting lateral upper top walls 26 and 28 integral with the lateral walls 20 and interconnected by the overlap portion 30 of the top wall 28 extending around the upstanding portion 32 of the top wall 26.

Disposed beneath the lateral upper top walls 26 and 28 and integral with the front and rear walls 16 and 18 respectively are front and rear slanting lower top walls 34 and 36 respectively. The lower top wall 34 is movable from its slanting position shown in FIGURES 1 and 3 to a vertical pouring spout position (not shown) after

2

the user tears the adjacent part of the overlapping portion 30 away from the upstanding portion 32, as is known to those familiar with this type of milk carton.

The foldable handle 14 consists of top and bottom tabs 5 or upper and lower attachment portions 38 and 40 respectively secured as by adhesives to the rear top wall 36 and the bottom wall 22 respectively, and an intermediate portion 42 extending upward from the bottom tab 40 at a fold or hinge line 43 therebetween, and 10 a reversely-bent connecting portion 44 interconnecting the upper end of the intermediate portion 42 and the lower end of the top tab 38 at fold lines or hinge lines 46 and 48 therebetween.

In the use of the invention, when the carton 10 is 15 packed in crates or in showcases or the like, or stored in refrigerators, the handle unit 14 is maintained in its folded position shown in FIGURES 1 and 2 with its intermediate portion 42 folded flat against the rear wall 18 of the carton unit 12. The upper part 50 of the intermediate handle portion 42 is then folded face-to-face with the reversely-bent portion 44 at the hinge line 46. The intermediate handle portion 42 is normally maintained in this position either by the natural adhesion of the waxed surfaces or by the use of an adhesive, preferably a pressure-sensitive adhesive. Such adhesives are well-known to those skilled in industry and available under various brand names on the open market.

To pour milk from the carton 10, the user exposes the 30 spout portion or front top wall 34 in the usual way by tearing away a forward part of the overlap portion 30 and by thereafter pulling the front top wall 34 upward into an approximately vertical position by a finger, fork or by other suitable means. By the use of a fork or other suitable tool, or by the finger nails, the user 35 then pulls the intermediate handle portion 42 from its face-to-face folded position of FIGURE 1 to its unfolded position of FIGURE 3. During such unfolding, the handle portions 38 and 50 straighten out at their hinge lines 48 and 46, thereby providing a space 52 between 40 the rear carton wall 18 and the intermediate handle portion 42 for insertion of the finger. The carton unit 12 is then conveniently held between the thumb and fingers while the backs of the fingers or the back of the palm rest against the intermediate handle portion 42. Pouring 45 can then be carried out precisely, without spilling the milk and without danger of slippage or dropping of the carton.

After pouring, the user may leave the handle unit 14 in its unfolded position of FIGURE 3, or he may fold it 50 again into its folded position of FIGURE 1 by pushing the intermediate handle portion 42 into face-to-face engagement with the carton rear wall 18 by reversing the foregoing procedure.

The modified handle-equipped carton, generally designated 60, shown in FIGURE 4 includes a carton unit 62 similar in all respects to the carton unit 12 of FIGURES 1 to 3 inclusive and consequently having its component parts designated with the same reference numerals. The handle unit 64, however, is of slightly different construction in that it has top and bottom tabs 66 and 68 secured respectively to the top rear wall 36 and bottom wall 22 of the carton unit 62 and hinge lines 70 and 72 respectively, connecting them respectively to overlapping upper and lower intermediate portions 74 and 76. These are 60 connected in overlapping relationship by a flexible connecting band 78. The connecting band 78 has an upper part 80 connected at a hinge line or fold line 82 to a reversely-bent part 84, the upper end of which is connected at a hinge or fold line 86 with the upper end of the lower portion 88 of the connecting band 78. The overlapping or reversely-bent portion 84 in the modification 60 of FIGURE 4 is thus located remote from both the upper

and lower fold lines or hinge lines 70 and 72 respectively of the handle unit 64.

In the use of the modified handle-equipped milk carton 60 of FIGURE 4, the same general procedure as that described above is followed as in the use of the handle-equipped milk carton 10 of FIGURES 1 to 3 inclusive. This procedure moves the intermediate handle portion 74 from its solid-line folded position to its dotted-line unfolded position shown in FIGURE 4. An adhesive may also be used to secure the intermediate handle portion 74 temporarily in its folded position, or the adhesive properties of the coating wax of the carton may be relied on for this purpose as described above. The handle unit 64 of the carton 60 may be restored to its folded position by reversing the foregoing procedure, causing the component parts to hinge or pivot around the hinge lines 70, 82, 86 and 72.

While the present invention has been described in connection with a milk carton, it is equally adaptable for use with other types of containers of whatever cross-section, whether rectangular or circular, and for solids as well as liquids. The invention, for example, may be used in connection with cereal containers to aid the user in pouring corn flakes or other cereals from the container.

The present invention is especially useful in containers which are bulky and heavy so as to be difficult to hold in the fingers. This is especially true where the container has been coated with a slippery waterproofing material such as wax or plastic which renders it easy to slip out of the fingers.

To hold the handle temporarily in its folded position, a suitable adhesive, such as a conventional pressure-sensitive adhesive, may be applied either to the inside of the handle, or to the adjacent portion of the container, or to both.

In the operation of the invention, instead of inserting the hand between the handle and the carton, as described above, the user may grasp the handle directly in his fingers without grasping the container.

What I claim is:

A handle-equipped closed container, comprising an

elongated vertically-disposed closed receptacle having a bottom wall, side walls and a top wall,

said top wall including an upper top wall portion and a lower top wall portion disposed below said upper top wall portion and defining a recess beneath said upper top wall portion;

and an elongated vertically-disposed foldable handle structure having at its lower end a lower attachment portion secured to said bottom wall,

said handle structure having an intermediate portion hingedly connected at its lower end to said lower attachment portion,

said handle structure also having an upper attachment portion secured to said lower top wall portion within said recess,

said handle structure also having a foldable connecting portion bent reversely to said intermediate portion and hingedly connected at its upper end to the upper end of said intermediate portion and hingedly connected at its lower end to said upper attachment portion,

said connecting portion in the folded position of said handle structure lying beneath said upper top wall portion within said recess and swingable out of said recess into an extended position approximately aligned with said upper attachment portion, whereby in the folded position of said handle structure said upper attachment portion and connecting portion lie within said recess within the confines of said side walls, said lower attachment portion lies beneath said bottom wall, and only said intermediate portion lies outside the confines of said side walls of said receptacle, namely in a position disposed flat against one of said side walls.
